COMBINATION FLUID DISPENSER AND BRUSH FOR CLEANING UPHOLSTERY OR THE LIKE

Howard A. Anderson, Pittsburgh, Pa., assignor to Bissell
Inc., Grand Rapids, Mich., a corporation of Michigan

Filed May 14, 1962, Ser. No. 70,103

Term of patent 14 years

(Cl. D9—2)

Fig. 1.

Fig. 2.

FIGURE 1 is a top plan view of a combination fluid dispenser and brush for cleaning upholstery or the like embodying my new design;

FIGURE 2 is a side elevation thereof, the opposite side being substantially the same in appearance;

FIG. 3 is a bottom plan view thereof;

FIG. 4 is a front end elevation thereof; and
FIG. 5 is a rear end elevation thereof.

I claim:

The ornamental design for a combination fluid dispenser and brush for cleaning upholstery or the like, substantially as shown and described.
